UNITED STATES PATENT OFFICE.

HENRY D. AUPKE, OF SHARPSBURG, PENNSYLVANIA.

WRENCH.

SPECIFICATION forming part of Letters Patent No. 783,813, dated February 28, 1905.

Application filed September 3, 1904. Serial No. 223,267.

To all whom it may concern:

Be it known that I, HENRY D. AUPKE, a citizen of the United States of America, residing at Sharpsburg, in the county of Allegheny and State of Pennsylvania, have invented certain new and useful Improvements in Wrenches, of which the following is a specification, reference being had therein to the accompanying drawings.

This invention has relation to certain new and useful improvements in wrenches, and more particularly to that type commonly known as "spanner-wrenches," which are employed for removing nuts from the spindles of axles and the like; and the object of this invention is to provide a novel form of wrench which may be quickly adjusted to the nut and retained thereon until the nut is removed and the wrench disengaged from the nut.

Referring to the drawings accompanying this application, like numerals of reference indicate similar parts throughout the several views, in which—

Figure 1 is a perspective view of my improved wrench, showing the same applied to a nut which is to be removed from the end of an axle or spindle. Fig. 2 is an end view of the wrench. Fig. 3 is a view of the opposite end or handle portion of the wrench.

To illustrate the use of my improved wrench, I have shown the end of a spindle as designated by the reference-numeral 1, this end of the spindle carrying a nut 2, which is shown in dotted lines in Fig. 1 of the drawings. The wrench as preferably constructed consists of two semicylindrical shells 3 and 4, these shells having their sides cut away, as designated at 5, to reduce the weight of the same. In forming the semicylindrical shells 3 and 4 I retain at their ends the material 6 and 7 and form this material so that the shell 4 will be provided with flanges 8 and the shell 3 will be provided with depending flanges 9, which will engage the flanges 8 of the lower shell 15 and hold said shells together. To form the flanges 8 and 9, the material 6 and 7, retained in the ends of said shells, is drilled, as designated at 10 in the shell 3 and as at 11 in the shell 4, this construction being clearly shown in Fig. 3 of the drawings. The periph-

ery of each shell is constructed with diametrically opposite pins 12 12, whereby a metallic ring 14, which is carried upon the periphery of said shells, is retained thereon and prevented from becoming detached from the shell except when they are separated from one another, which is accomplished by placing the metallic ring 14 upon the end of the wrench and by sliding one shell without the other, as will be permissible by the construction shown in Fig. 3 of the drawings. Centrally of said tongs is provided the reinforcing-strip 15, which is formed integral with each shell, and the inner sides of the shells 3 and 4 opposite these reinforcing-strips are provided with collars 16 and 17, and the collar 16 of the shell 3 is provided with a screw-threaded aperture through which a screw-bolt 18 passes. This screw-bolt normally bears in the collar 17, and the screw-bolt is employed to adjust the shells 3 and 4 for different-sized nuts which are to be gripped by said wrench.

In forming the outer end of the wrench, which is adapted to grip the nut, I retain a portion of the material, as designated by the reference-numerals 19 19, and form the material of each of the shells 3 and 4 with angular sides 20 and 21, whereby the face of a nut may be readily gripped by the wrench.

The shells 3 and 4 comprising the wrench are formed with countersunk surfaces 22 22, and in these surfaces I form annular recesses 23 23 to receive a suitable lever for rotating the wrench in either direction.

In practice the ring 14 is moved rearwardly until it engages the pins 12 12, at which time the shells 3 and 4 of the wrench may be opened to such an extent as will be permitted by the metallic ring 14 and the connected ends of the shell. The wrench is then closed to embrace the nut in its jaws 19 19 and the ring slid forward on the cut-away edges to clamp the jaws in the said position. When the wrench is closed on the nut, any suitable lever is brought into play to rotate the wrench, the said lever being inserted in apertures 23 23. The screw-bolt may be adjusted when it is desired to grip nuts other than that shown in the accompanying drawings.

It will be noted that various changes may

be made in the details of construction, such as the shape and size of the wrench, without departing from the spirit and scope of the invention.

5 Having fully described my invention, what I claim, and desire to secure by Letters Patent, is—

1. A wrench comprising two sections having their corresponding ends detachably locked together by interlocking means formed integral with the sections, the edges of said sections having cut-away portions, and means arranged on said portions for holding said sections together.

15 2. A wrench comprising two semicylindrical sections having their edges partially cut away, a securing means on said sections adjacent said cut-away edges, and integral interlocking flanges on the edges for detachably locking 20 the sections together.

3. A wrench comprising two semicylindrical sections having cut-away edges, a ring arranged thereon and having its rearward movement arrested by pins on said sections, the rear ends 25 of said sections being removably locked to-

gether, and the forward ends formed with jaw-faces, an adjusting-screw on one of said sections for engagement with the opposing section, and said wrench being formed with suitable means to be engaged by any suitable 30 lever for rotating the wrench.

4. A wrench comprising two sections, the rear ends thereof being formed with flanges, the flanges of one section being flared to interlock with the flanges of the other section. 35

5. A wrench comprising two sections having flanges forming a fulcrum therefor, the flanges of one section projecting inwardly to embrace the flanges of the opposing section.

6. A wrench comprising two sections, flanges 40 on the rear end thereof, interlocking extensions on said flanges, the extensions on one section projecting inwardly and those on the other section projecting outwardly.

In testimony whereof I affix my signature in 45 the presence of two witnesses.

HENRY D. AUPKE.
